Inventor:
Joseph Komorous,
By appointment of
C. R. C., C. I. C.,
Attest:

UNITED STATES PATENT OFFICE.

JOSEPH KOMOROUS, OF RIVERSIDE, ILLINOIS, ASSIGNOR TO PARISIAN NOVELTY COMPANY, OF CHICAGO, ILLINOIS, A CORPORATION OF ILLINOIS.

RECEPTACLE.

Application filed June 19, 1922. Serial No. 569,546.

To all whom it may concern:

Be it known that I, JOSEPH KOMOROUS, a citizen of the United States, residing at Riverside, in the county of Cook and State 5 of Illinois, have invented a new and useful Improvement in Receptacles, of which the following is a specification.

My invention relates, more particularly, to improvements in savings banks of the 10 relatively small portable type and into which coins may be readily inserted and be withdrawable therefrom only upon opening the bank, preferably through the medium of a tool especially designed for this purpose, 15 this type of bank being commonly employed by savings bank institutions for distribution among their customers.

My primary object is to provide a novel, simple and economical construction of bank 20 structure of the general type above referred to, the parts of which may be readily assembled to close the bank for the reception of coins, and the parts thereof disassembled under a desirable degree of restraint to render 25 the contents of the bank accessible, and preferably require the use of a particular tool of unusual construction for opening the bank; and other objects as will be manifest from the following description.

30 Referring to the accompanying drawing:

Figure 1 is a plan view of a structure embodying my invention, the parts of the bank being shown in assembled and interlocked condition, with a tool, represented 35 by dotted lines, preliminarily positioned for unlocking the cover from the body portion of the bank. Figure 2 is a view in side elevation of the structure shown in Fig. 1, the tool referred to being shown in full lines.

40 Figure 3 is a face view of the inside of the cover section. Figure 4 is an edge view of the body portion of the bank with which the cover section cooperates. Figure 5 is a view in side elevation of a portion of the body of the bank, with the cover section removed. Figure 6 is a broken sectional view 45 taken at the line 6 on the Figs. 3 and 4 and viewed in the direction of the arrows, showing the tool preliminarily positioned for opening the bank. Figure 7 is a similar view taken at the line 7 on Fig. 3 and viewed in the direction of the arrow; and Figure 8, a perspective view of the tool for opening 50 the bank.

55 The structure shown comprises a hollow

body portion, represented at 9, forming the main portion of the bank-receptacle, this body portion being shown as formed of a cylindrical shell 10 and an end plate 11 closing one end of the shell, these parts being 60 rigidly connected together in any suitable way. The body portion 9 is shown as provided with a base portion 12 affording legs at which the structure is adapted to be supported. The structure also involves a removable cover, or end plate 13, formed as a part separate from the body portion 9 adapted to be releasably interlocked with the latter in a manner hereinafter described. 65

The shell 10 contains a coin-receiving slot 70 14 extending transversely of the axis of the shell and with a side opening 15 for viewing the contents of the bank. The coin slot 14 is equipped with guard means of any suitable construction and represented at 16, 75 for preventing retraction through the coin slot of coins deposited into the bank, the particular coin guard shown comprising a strip 17 of flexible material, such as leather, secured to the inner surface of the shell 10 80 and containing a slit extending lengthwise thereof and opposite the coin-insertion opening 14, this being of zigzag form. The end of the shell 10 opposite that at which the cap plate 11 is secured, is provided with 85 a series of inwardly-extending projections 18 which are formed preferably by indenting the edge of the shell as represented most clearly in Figs. 4 and 7. Located between adjacent ones of the projections 18 and in a 90 position, in the particular construction illustrated, in general line with the coin slot 14, is a pair of recesses 19, and extending in line with these recesses and set back from the edge containing them are two tool-receiving slots 20.

The cover section 13 which has rotation on the shell 10 at the end thereof opposite that equipped with the cap 11, except as restrained by the locking means hereinafter 100 described, is provided on its inner face with a series of projections 21 extending downwardly and in an outward direction as represented more clearly in Fig. 7, and with a pair of spring tongues 22 so spaced as to 105 register with, and enter, the recesses 19 when in registration therewith as hereinafter described. By preference, and in accordance with the illustrated showing, the projections 21 and tongues 22 are formed integrally 110

from a plate 21^a of spring metal which is rigidly secured to the inner face of the body portion of the plate 13. The projections 18 and 21 are so disposed that when the cover plate 13 is applied to the body portion 9 to form a closure therefor, and is rotated to a position in which the tongues 22, under their spring action, spring into the recesses 19 and thus hold the plate 13 against rotation until 10 these tongues are released from these recesses, the projections 21 will extend into overlapping relation to the projections 18 and prevent separation of the plate 13 from the body portion by relative movement of 15 these parts lengthwise of the receptacle, whereby the plate 13 will be locked against disengagement from the body portion.

To remove the plate 13 from the body portion it is necessary to first withdraw the 20 tongues 22 from a position in which they extend into the recesses 19 and then rotate this plate to a position in which the projections 21 and 18 are out of registration with each other, and this is accomplished in the particular construction illustrated by the use of 25 a tool which is adapted to be inserted into the openings 20 and manipulated to spring the tongues 22 to the position stated. Such a tool is represented in the drawings, particularly Fig. 8, this tool comprising a body portion 23 provided at one end with spaced-apart depending leg portions terminating in 30 forwardly-projecting extensions 25 which are spaced apart a sufficient distance to permit them to enter the slots 20, as represented in the drawings, to engage the tongues 22 and force them out of the recesses 19, the operator, while maintaining the tool in the 35 position to which it is operated as stated, rotating the plate portion 13 to a position in which the projections 18 and 21 are in non-overlapping position.

The feature of so forming the projections 18 that their under surfaces are curved 40 crosswise thereof, is of advantage inasmuch as thereby they exert an action, in the nature of a cam action, against the projections 21 in the act of rotating the cover on the body member, thereby drawing the cover tightly 45 to place.

While I have illustrated and described a particular construction involving my invention, I do not wish to be understood as intending to limit it thereto as the same may 50 be variously modified and altered without departing from the spirit of my invention.

What I claim as new, and desire to secure by Letters Patent, is:

1. In a receptacle, the combination of a 60 body-member containing recesses, a cover section rotatable on said body-member and provided with a plurality of separately deflectable tongues adapted to enter said recesses respectively in one position of said 65 cover on said body-member to lock said

cover against rotation on said body member, and means on said body-member and cover adapted in the rotation of said cover to a position in which said tongues register with said recesses, to prevent separation of said 70 cover and body-member.

2. In a receptacle, the combination of a 75 body-member containing recesses, a cover section rotatable on said body-member and provided with a plurality of separately deflectable tongues adapted to enter said recesses respectively in one position of said cover on said body-member to lock said cover against rotation on said body-member, and series of projections on said cover and 80 body-member adapted in the rotation of said cover to a position in which said tongues register with said recesses, to extend in mutually overlapped relation and prevent separation of said cover and body-member. 85

3. In a receptacle, the combination of a 90 body member containing a series of inwardly-extending projections at its open end the under surfaces of which are curved in a direction crosswise of the projections, a cover 95 rotatable on said body-member and having portions adapted to extend under said projections in the rotation of said cover to a certain position on said body-member, and releasable means for preventing rotation of 100 said cover out of a position in which said projections are lapped.

4. In a receptacle, the combination of a 105 body-member having portions thereof deflected inwardly to provide a series of inwardly-extending projections at its open end the under surfaces of which are curved in a direction crosswise of the projections, a cover 110 rotatable on said body-member and having portions adapted to extend under said projections in the actuation of said cover to a certain position on said body-member, and releasable means for preventing rotation of said cover out of a position in which said projections are lapped. 115

5. In a receptacle, the combination of a 120 body member the edge-portion of its side wall being unflanged and containing a series of inwardly-extending projections and a recess which extends in the plane of said side wall, a cover-section rotatable on said body-member and having projections and adapted to interlock with said projections on the body-member when said cover-section is 125 rotated to a certain position thereon, and a tongue on said cover-section having its end extended to ride on the edge section of said wall adapted to enter said recess when said cover-section is in said position for releasably locking said cover-section against rotation.

6. In a receptacle, the combination of a 130 body member the edge-portion of its side wall containing a series of inwardly-extending projections the under surfaces of which

- are curved in a direction crosswise of the projections, a cover-section rotatable on the side-wall of said body-member and having projections adapted to interlock with said 5 projections on the body-member when said cover-section is rotated to a certain position thereon, and means releasably locking said cover-section in said position.
7. In a receptacle, the combination of a 10 body-member having a side wall the edge portion of which is unflanged, portions of said wall being deflected inwardly to provide a series of inwardly-extending projections, a cover-section rotatable on the side 15 wall of said body member and having projections adapted to interlock with said projections on the body-member when said cover-section is rotated to a certain position thereon, and means releasably locking said 20 cover-section in said position.
8. In a receptacle, the combination of a body-member having a side wall the edge portion of which is unflanged, portions of said wall being deflected inwardly to provide a series of inwardly-extending projections, a cover-section rotatable on the side 25 wall of said body-member and having radially-extending projections adapted to interlock with said projections on the body-member when said cover-section is rotated to a certain position thereon, and means releasably locking said cover-section in said position.
9. In a receptacle, the combination of a 30 body-member, portions of its side wall being deflected inwardly to provide a series of inwardly-extending projections, said side wall containing a recess extending in the plane of said side wall, a cover-section rotatable on said side wall and having projections adapted to interlock with said projections on the body-member when said cover-section is rotated to a certain position thereon, and a tongue on said cover-section having 35 its end extended to ride on the edge section of said wall adapted to enter said recess when said cover-section is in said position for releasably locking said cover-section against rotation.
10. In a receptacle, the combination of a 40 body-member the edge-portion of its side wall having portions thereof deflected inwardly to provide a series of inwardly-extending projections, the under surfaces of 45 said projections being curved in a direction crosswise of the projections, a cover-section rotatable on the side-wall of said body-member and having projections adapted to interlock with said projections on the body-member when said cover-section is rotated to a certain position thereon, and means releasably locking said cover-section in said position.
11. In a receptacle, the combination of a 50 body-member containing recesses, a cover-section rotatable on said body-member and provided with a plurality of separately deflectable tongues adapted to enter said recesses respectively in one position of said cover on said body-member to lock said 55 cover against rotation on said body member, and means on said body-member and cover adapted to the rotation of said cover to a position in which said tongues register with said recesses, to prevent separation of said cover and body-member, said body-member containing a plurality of openings for receiving the tongue-engaging portions of means for deflecting the tongues out of engagement with said recesses. 60
12. In a receptacle, the combination of a body member, a cover member therefor, and means for holding said cover member on said body member and involving a plurality of separately deflectable portions, said deflectable portions being located closely adjacent the side wall of the structure, and one of said members containing a plurality of openings for receiving portions of a key for deflecting said deflectable portions to releasing 65 position.
13. In a receptacle, the combination of a body-member having a side wall the edge portion of which is unflanged, portions of said side wall being deflected inwardly to 70 provide a series of inwardly-extending projections, a cover-section rotatable on the side wall of said body-member and having projections adapted to interlock with said projections on the body-member when said 75 cover-section is rotated to a certain position thereon, and means carried by the cover and registering with recesses in the edge of the side wall to releasably lock said cover-section in said position. 80
14. In a receptacle, the combination with a body-member having a side wall the edge portion of which is unflanged, portions of said wall being deflected inwardly to provide a series of inwardly-extending projections, a cover-section rotatable on the side 85 wall of said body-member and having radially-extending projections adapted to interlock with said projections on the body-member when said cover-section is rotated to a certain position thereon, and tongues located between a pair of projections for releasably locking said cover-section in said position. 90
15. In a receptacle, the combination of a 95 body member, a cover member therefor, and means for holding said cover member on said body member and comprising a plurality of separately independently deflectable portions and each of which is required to be deflected to release the cover member, one of said members being so apertured as to receive a two-pronged key for simultaneously deflecting said deflectable portions. 100

JOSEPH KOMOROUS.
